UNITED STATES PATENT OFFICE.

CHARLES HERBERT OCUMPAUGH, OF ROCHESTER, NEW YORK.

SASH-BAND FASTENER.

SPECIFICATION forming part of Letters Patent No. 679,904, dated August 6, 1901.

Application filed July 6, 1899. Serial No. 722,981. (No model.)

To all whom it may concern:

Be it known that I, CHARLES HERBERT OCUMPAUGH, a resident of Rochester, in the county of Monroe and State of New York, have invented certain new and useful Improvements in Sash-Balances; and I do hereby declare the following to be a full, clear, and exact description of the invention, such as will enable others skilled in the art to which it 10 pertains to make and use the same.

The invention relates to sash-balances, and has for its object to provide convenient, secure, and durable means of attaching weights to the metal bands or other flexible connections of the weights and sash.

The invention consists in the construction hereinafter described, and pointed out in the claims.

In the accompanying drawings, Figure 1 is 20 a broken section of the window and sash-balance. Fig. 2 is an enlarged perspective of a detail. Fig. 3 is a perspective of the improved device, and Fig. 4 is a like view of another form of the device.

25 Numeral 1 denotes a sash, and 2 is a flexible weight-support, a metal band being indicated in the present instance. The band may be fixed to the sash in any usual or convenient way.

30 3 denotes an apertured piece or anchor of a usual construction to which the band is fastened, which piece is seated in a suitable opening in the sash.

4 35 denotes a pulley over which the band passes in usual manner, and 5 indicates a weight attached to the band. Said weight in use will ordinarily be situated within the window-casing 6.

The parts thus far described are well known 40 and are not of the present invention. They may be varied in any desired manner not inconsistent with the improvement hereinafter pointed out.

45 Numeral 8 denotes a weight-supporting coupling, preferably made of wire and having approximately the form of said numeral. The upper part or loop 7 of said coupling is connected to the band by means of a ring 9, which ring is held by the end of the band doubled upon itself, as indicated at 10. Said coupling also carries a ring 11, which engages the folded end 10' of the band on its exterior.

This ring 11 is situated above ring 9, substantially as represented, and in practice largely sustains the weight, the ring 9 serving mainly to hold ring 11 on the band; but it will be understood that in operation ring 11 bears upon ring 9 at 9' and that the stress caused by the weight is transmitted to the band at the bottom of its bend. The ring 11 55 also performs the important function of preventing the straightening out of the folded end of the band. This ring cannot in use be separated from the band by a pull without passing over ring 9, and the latter is made of 60 such size as to prevent it. It is obvious that both rings can be released from the band by moving them until ring 9 escapes its folded end and that they can be applied to the band by a reverse operation.

70 The weight is connected to and suspended from the lower loop of the coupling 8 in any usual manner. It may be provided with an opening 12 to permit the insertion of the wire end 13, which may be bent into a hook form 75 either before or after its connection with the weight and coupled to a similar hook 14 on the other end of the coupling-wire. These hooks may be clenched upon each other, if desired, to obviate accidental escape of the 80 weight or the straightening of the wire.

75 The improvement contemplates variations in form which are merely mechanical and do not involve any departure from the construction and principle of operation herein set 85 forth.

I am aware that a weight-supporting bail or link has been held upon a wedge-shaped block by means of a ring-like block bearing oppositely upon the folded parts of a band 90 and drawn upon the band-folds by the weight, and such matter is not of my invention, which is characterized by a so-called binding or clamping device, such as ring 11. This operates on one side only of the band and forms 95 and maintains a bend in both band-folds, and which can be economically made of wire.

I am aware that bent-wire couplings are well known. My improvement is characterized by a wire crossed upon itself and bent 100 to form two openings, one on each side of the crossing, the wire terminating adjacent one of said openings in detachable hooks, whereby the coupling can be opened to receive a con-

necting device or devices and then closed for use.

Having thus described my invention, I claim—

- 5 1. A sash-band, a weight meditately supported thereby, a loose ring through which one end of the band is passed and about which it is folded back upon itself, and means independent of said ring to bind the band to the ring, said means bearing on one side only of the band-fold and above the ring and immediately supporting the weight to form and maintain a bend in the folded part of the band adjacent to the ring through the pull of said weight, said means being loosely connected to and separable from both the band and the weight.
- 10 15

2. A sash-band, a weight supported thereby, a ring through which one end of the band is passed and about which it is folded back upon itself, and means independent of the ring to bind the band to the ring by the pull of the weight, said means comprising a second ring bearing loosely on one side of the part of the fold next the end of the band and above the ring.

In testimony whereof I have signed this specification in the presence of two subscribing witnesses.

CHARLES HERBERT OCUMPAUGH.
